(57) **CLAIM**

The ornamental design for a rigid barrier for bracing tubular flexible conforming filter devices with respect to curb and/or stormwater drains, as shown and described.

DESCRIPTION

FIG. 1 is a perspective view of a rigid barrier for bracing tubular flexible conforming filter devices with respect to curb and/or stormwater drains showing my new design; FIG. 2 is a perspective view comparable to FIG. 1, except on an enlarged scale;

FIG. 3 is a front elevational view taken in the direction of the arrows III-III in FIG. 2;

FIG. 4 is a rear elevational view taken in the direction of the arrows IV-IV in FIG. 2;

FIG. 5 is a top plan view taken in the direction of arrows V-V in FIG. 3;

FIG. 6 is a left side elevational view taken in the direction of arrows VI-VI in FIG. 3;

FIG. 7 is a right side elevational view taken in the direction of arrows VII-VII in FIG. 3;

FIG. 8 is a perspective view comparable to FIG. 1, except showing an alternate manner of use; and,

FIG. 9 is a perspective view comparable to both FIGS. 1 and 8, except showing still another alternate manner of use. The broken lines in the drawing represent environmental subject matter that forms no part of the claimed design.

1 Claim, 8 Drawing Sheets
